(57) **CLAIM**

The ornamental design for a faucet assembly, as shown and described.

DESCRIPTION

FIG. 1 is a front perspective view of a faucet assembly showing my design;

FIG. 2 is a front elevational view thereof;

FIG. 3 is a rear elevational view thereof;

FIG. 4 is a left side elevational view thereof; the right side elevational view being a mirror image thereof; and,

FIG. 5 is a top plan view thereof.

The broken lines are included for the purpose of illustrating portions of the faucet assembly that forms no part of the claimed design.

1 Claim, 5 Drawing Sheets

FIG. 1

FIG. 4

FIG. 5
